(57) **CLAIM**

The ornamental design for a hanging light fixture as shown and described.

DESCRIPTION

FIG. 1 is an isometric view of a hanging light fixture showing our new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof;

FIG. 8 is an isometric view of a hanging light fixture showing an alternate embodiment of including the design of FIGS. 1-7;

FIG. 9 is a front view thereof;

FIG. 10 is a rear view thereof;

FIG. 11 is a left side view thereof;

FIG. 12 is a right side view thereof;

FIG. 13 is a top plan view thereof;

FIG. 14 is a bottom plan view thereof;

FIG. 15 is an isometric view of a hanging light fixture showing another alternate embodiment including our new design of FIGS. 1-7;

FIG. 16 is a front view thereof;

FIG. 17 is a rear view thereof;

FIG. 18 is a left side view thereof;

FIG. 19 is a right side view thereof;

FIG. 20 is a top plan view thereof;

FIG. 21 is a bottom plan view thereof;

FIG. 22 is an isometric view of a hanging light fixture showing another alternate embodiment including our new design of FIGS. 1-7;

(Continued)

FIG. 23 is a front view thereof;
 FIG. 24 is a rear view thereof;
 FIG. 25 is a left side view thereof;
 FIG. 26 is a right side view thereof;
 FIG. 27 is a top plan view thereof; and,
 FIG. 28 is a bottom plan view thereof.

The broken lines depicting the remainder of the light fixture show features that form no part of the claimed design. FIGS. 1-7 show the light fixture with a symbolic break in its length, and the appearance of any portion of the light fixture between the respective adjacent break lines forms no part of the claimed design.

1 Claim, 16 Drawing Sheets
